Carpets

UNITED STATES PATENT OFFICE.

ARTHUR M. KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,643, dated March 12, 1872.

To all whom it may concern:

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration, forming part of the specification.

This invention relates to a new design for carpets, whose peculiar characteristic consists

in the arrangement of heavy and lighter ogee lines, A A, which embrace at their ends small rosettes B B, and form between them the larger central figures C C, as shown.

I claim as my invention—

The design for a carpet containing the ogee lines A, rosettes B, and figures C C, as shown.

ARTHUR MAZEPPA KING.
